By # UNITED STATES PATENT OFFICE.

GEORGE V. BURRIS, OF COURTLAND, CALIFORNIA.

SIGNAL.

1,374,427.

Specification of Letters Patent. Patented Apr. 12, 1921.

Application filed November 12, 1919. Serial No. 337,528.

To all whom it may concern:

Be it known that I, GEORGE V. BURRIS, a citizen of the United States, residing at Courtland, in the county of Sacramento and State of California, have invented certain new and useful Improvements in Signals; and I do hereby declare the following to be a full, clear, and exact description of the invention, such as will enable others skilled in the art to which it appertains to make and use the same.

This invention relates to railroad crossing signals, and the primary object of the invention is to provide an improved means for warning the occupants of road vehicles of their approach to a railroad crossing, so that suitable precautions can be taken.

Another object of the invention is to provide an improved signal adapted to be actuated by a road vehicle positioned across a roadbed, bridge, culvert or the like at a distance from the railroad track so that the attention of the occupants of the vehicle will be called to the fact that they are approaching a railroad crossing.

A further object of the invention is to provide an audible signal, which is adapted to be actuated by a vehicle passing over the same, so as to warn the occupants that danger is ahead, such as a railroad crossing, a dangerous curve, or the like.

A still further object of the invention is to provide an improved vehicle actuated signal of the above character, which is durable and efficient in use, one that is simple and easy to manufacture, and one that can be placed upon the market at a reasonable cost.

With these and other objects in view, the invention consists in the novel construction, arrangement and formation of parts, as will be hereinafter more specifically described, claimed and illustrated in the accompanying drawings, forming a part thereof, in which:

45 Figure 1 is a view of a roadbed, showing the improved signal embedded therein.

Fig. 2 is a longitudinal section through the same.

50 Fig. 3 is a transverse section taken on the line 3—3 of Fig. 2.

Fig. 4 is a detail fragmentary section taken on the line 4—4 of Fig. 2.

Fig. 5 is a detail section taken on the line 5—5 of Fig. 4.

55 Fig. 6 is a detail enlarged view of the bell

removed from its signal actuating mechanism.

Referring to the drawings in detail, wherein similar reference characters designate corresponding parts throughout the several views, the numeral 1 generally indicates the improved signal which as shown is embedded in a roadway and extends transversely of the same, but it is to be understood that the same can be built in the floor- 65 ing of a bridge, if so desired.

The signal 1 includes a frame 3, which is adapted to be embedded in the roadway 2 and includes a pair of spaced parallel supporting beams 4 connected together at their upper edges by the transversely extending cross pieces 5. The cross pieces 5 have secured to their lower surface at the central portion thereof the longitudinally extending supporting plate 6 which carries the bell 75 or other audible signal mechanism 7.

The cross pieces 5 have mounted on their upper surface the longitudinally extending plates or bridge pieces 8, which extend entirely across the roadway. As shown, the 80 plates are three in number and constitute a portion of the roadbed. The central plate 8 is secured to the side plates by means of hinges 9 and the central plate is held in an elevated position by means of expansion coil 85 springs 10 which are coiled around the guide rods 11 secured to and depending from the lower surface of the central plate. The plates 8 extend downwardly at an incline to the central plate and have their 90 lower edges resting on the upper surface of the cross pieces 5 for sliding movement. The guide rods 11 extend entirely through the member 6 and have threaded on their lower ends nuts 12 which limit the upward 95 movement of the rod and the plates 8. The upper terminals of the rods 11 are provided with heads 13 which are preferably countersunk in the upper surface of the central plate. 100

Thus, it will be seen that the central plate 8 is normally held in a raised position by the expansion spring 10 and when a vehicle rides over the plate, the same will be depressed, the purpose of which will be 105 hereinafter more fully described. The cross pieces 5 have also secured to their upper surface adjacent to the outer ends thereof the longitudinally extending pieces 14, which are arranged in spaced relation to 110

the free edges of the side plates 8 and form stops for the side plates when the plates are depressed and also form a tread surface for the signal.

5 The lower edges of the longitudinally extending beams 4 are provided with anchoring plates 15 which extend in opposite directions at right angles to the beams and form an effective means for preventing the 10 displacement of the frame. The frame is also provided with end pieces 16, which prevent the entrance of dirt and the like into the frame.

15 Lateral movement of the plates 8 is prevented by means of the flat guide rods 16 which are secured to the lower surface of the side plates 8 and extend outwardly therefrom and slidably engage the upper surface of the beams 4 intermediate the cross pieces 5. The guide bars 16 are received in U-shaped guide brackets 17, which have their lower terminals twisted at right angles to provide attaching means 18, which receive suitable fastening elements 19 which 20 extend into the inner surface of the beams 4 and hold the guide brackets against displacement.

25 The signal bell 7 includes a base plate 20, which is secured to the lower surface of the member 6 adjacent to the central portion thereof and the same is provided with an actuating rod 21, which is normally held in its raised position by means of a spring 22. The actuating rod 21 is provided with an 30 actuating piece 23, which engages the lower surface of the central plate 8. The rod is slidably received in suitable openings formed in the base plate 20 and the member 6 and the base plate is provided with suitable guide sleeves 23 for guiding the same in its movement. The lower end of the rod is pivotally secured to a lever 24, which is pivotally secured intermediate its ends upon a pivot pin 25 and a depending bracket 40 26 carried by the base plate. The free end of the lever is enlarged as at 27 and is provided with an arcuate recess 28, one wall of which is provided with a plurality of ratchet teeth 29 which are adapted to engage a pinion 30 rotatably mounted upon a shaft 31 carried by the bracket. The pinion 30 has secured thereto the clapper arms 32 which are mounted eccentrically to the bell 33, which is secured to the bracket 26.

55 In operation of the improved device, when a vehicle rides over the plate 8, the weight of the same will depress the plate against the tension of the coil springs 10 and thus force the operating rod 21 downwardly and rotate the pinion 30 and throw the clapper arms 32 into engagement with the bell, which

will call the attention of the occupants of the vehicle to the fact that they are approaching a railroad crossing or other difficulty in which precaution should be used. 65

Signal posts 35 are carried by the pieces 14 adjacent each end thereof having their upper terminals bent angularly as at 36 and carrying suitable cross arms 37 which have written thereon suitable legends for warning the applicants of the vehicle of the danger ahead. 70

While the signal mechanism can be placed any suitable distance away from the railroad crossing, it has been found that the 75 preferred distance is approximately eight hundred feet.

In practice, I have found that the form of my invention illustrated in the accompanying drawings and referred to in the above description, as the preferred embodiment, is the most efficient and practical; yet realizing the conditions concurrent with the adoption of my device will necessarily vary, I desire to emphasize that various 85 minor changes in details of construction, proportion and arrangement of parts may be resorted to, when required without sacrificing any of the advantages of my invention as set forth. 90

What I claim as new is:

A signal comprising a supporting frame adapted to be placed in a roadway and embedded therein, a sectional tread member mounted on said supporting frame, a signal supporting member positioned within said supporting frame beneath the central section of said tread member, a signal carried by said signal carrying member, an operating rod for said signal extending upwardly 100 through said signal carrying member and engaging the under face of the central section of said tread member, means engaged around said signal operating rod to resiliently retain the latter in unoperated position and in engagement with the under face of said central section of the tread member, means positioned between said central section of the tread member and said signal carrying member to resiliently retain the 110 central section of said tread member in raised position, guide arms for said tread member connected with the outer sections thereof, and means to receive said guide arms and retain the latter against lateral 115 movement during operation of the signal.

In testimony whereof I affix my signature in presence of two witnesses.

GEORGE V. BURRIS.
